UNITED STATES PATENT OFFICE

2,219,517

HEATING APPARATUS

Homer D. Dufault, Easthampton, Mass., assignor
to Holyoke Heater Company, Holyoke, Mass., a
corporation of Massachusetts

Application August 21, 1939, Serial No. 291,232

11 Claims. (Cl. 126—53)

This invention relates to improvements in heating apparatus and is directed more particularly to improvements in gas heating apparatus.

The principal objects of the invention are directed to the provision of heating apparatus adapted to be located in a compartment of a gas range or the like and said apparatus is characterized by a water heater which is insertable in and removable from the apparatus so that it may be used when desired. By means of the novel construction of the invention the water heater when inserted in the heating apparatus may be rendered inoperative when desired.

Modern gas ranges such as are used for domestic purposes are usually provided with open burners on the upper side thereof and both an oven-broiler compartment and one or more other compartments therebelow.

According to novel features of the invention, a heating unit is provided that is adapted to be located in one of said other compartments of a gas range and it may in turn have a water heater inserted therein with means for directing heat through the heater or for directing it therearound. In this way the heating unit may be utilized for heating water or for general heating purposes.

Various other novel features and advantages of the invention will be hereinafter more fully referred to in connection with the accompanying description of the preferred form of the invention, reference being had to the drawing, wherein:

Fig. 1 is a perspective view of a range showing the heating apparatus of the invention disposed in a compartment thereof;

Fig. 2 is a front elevational view of the heating apparatus of the invention;

Fig. 3 is an enlarged transverse sectional elevational view through the upper part of the main part of the heating apparatus shown in Fig. 2;

Fig. 4 is a side elevational view of the secondary chamber of the heating apparatus;

Fig. 5 is a perspective view of the water heater unit of the invention;

Fig. 6 is a transverse sectional elevational view through the water heater shown in Fig. 5; and

Fig. 7 is a partial perspective view showing the rear end of the water heater illustrated in Figs. 5 and 6.

Referring now to the drawing more in detail, the invention will be fully described.

A gas range R is represented in Fig. 1 which has in its lower portion an oven, broiler compartment or the like having a door 2 and an adjacent compartment provided with a door 4. The heating unit of the invention represented gen-

erally by 6 is receivable in said adjacent compartment and a wall 8 of the compartment is provided with a grill 10 so constructed that heat from the heating unit may be utilized for heating the room.

The heating unit consists of primary and secondary chambers 12 and 14. Front, rear, side, upper and lower walls numbered 16, 18, 20, 22 and 24 respectively form the primary chamber.

Front, rear, side, upper and lower walls numbered 26, 28, 30, 32, and 34 respectively form the secondary chamber. Said chambers 12 and 14 are connected adjacent their upper sides by one or more hollow connections 36.

A gas burner of some desired form represented by 38 is disposed in the lower portion of the chamber 12 and it will be suitably connected to the gas supply. The products of combustion or heat travel upwardly through chamber 12 through connections 36 into chamber 14.

A baffle 42 in chamber 14 causes the hot gases to flow downwardly and then upwardly to a flue 42' in the rear wall 28 of said chamber. Preferably spaced fins 44 of relatively thin metal are provided on the walls of the chambers as shown to facilitate the radiation of heat.

An opening 50 is provided in the front wall 16 of chamber 12 for receiving a water heater W shown in Figs. 5 and 6, and the side walls of the said chamber carry supports 52 for said water heater. The latter includes front and rear end members 54 and 56 between which extend a plurality of tubes 58.

The front end member 54 is provided with hollow portions 60 as shown in Fig. 5 which connect the upper tubes 58. The rear end member 56 is preferably hollow to provide interconnection between the tubes 58 and pipes 57 may be connected to the rear member as shown in Fig. 7 for connecting the water heater to a hot water supply system. The tubes 58 may be provided with fins, quills or other heat absorbing properties such as indicated by 59.

Side plates 62 and an upper plate 64 extend between the end members to provide an enclosure 45 for the tubes 58 as shown in Fig. 6. There are spaces 66 between the upper sides of plates 62 and plate 64.

Brackets 68 may be associated with end members 54 and 56 and these will have a longitudinally extending rod 70 journaled therein. A gate or damper 72 is fixed to the rod 70 and said rod has an offset end portion in the form of a crank 72' to facilitate rotating of the rod.

Brackets 76 having horizontally disposed sup-

porting portions 18 are secured to the side walls 62 of the water heater. Thus the heater may be inserted in the opening 50 in the front wall of chamber 12 in such a way that members 18 rest on supports 52 whereby the heater is suspended within the said chamber.

With the water heater in place in the chamber, the opening 50 may be closed by a plate 80 secured in place by screws 82.

10 A lever 84 is pivoted to wall 16 of the heater and a link 85 connected thereto at 86 receives the end of crank 72' of rod 70. By swinging lever 84 up and down the gate 72 is caused to swing between its open position shown in Fig. 6 upwardly to closed position where it closes the space between walls 62 of the water heater.

In Fig. 1 the lever 84 is shown in the closed position of the gate. The lever 84 is more or less spring like and an abutment 86' is provided so that said lever 84 may be sprung thereunder to hold lever 84 in the position shown.

The heating unit may be inserted in the compartment of the gas range and where it is desired to heat water the water heater may be inserted in the chamber 12 of the heater.

25 In all cases the gas burner will be connected to the gas supply and the flue 42 will be connected to the stack. Where the water heater is used the crank 72' thereof will be connected to link 85.

30 With the gate 72 swung upwardly to closed position heat passes up and around the water heater, the walls of the chamber being heated so that heat passes out through the grill 10.

35 When it is desired to direct more heat onto the tubes of the water heater, the gate is moved to open position by releasing lever 84 and swinging it upwardly. With the gate in the open position shown in Fig. 6 heat passes upwardly

40 through the water heater and out slots 66 thereof.

45 It will be observed that the heating apparatus may be utilized in the compartment of the range with or without the water heater being used. As explained when the water heater is in place the gate provides the means for directing heat therethrough or around the same as may be desired.

50 While I have described the invention in great detail and with respect to the present preferred form thereof, it is not desired to be limited thereto since changes and modifications may be made therein without departing from the spirit and scope of the invention. The invention may be embodied in other specific forms without departing 55 from the essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

55 What it is desired to claim and secure by Letters Patent of the United States is:

1. The combination with a compartment of a gas range of a heating unit comprising, a closed chamber having an opening in a wall thereof and a burner therein, a secondary closed chamber having a flue therein, a tubular connection between the upper parts of said chambers, a water heater removably disposed in the first-named chamber adjacent said opening therein, said water heater including spaced longitudinally-extending tubes and connecting headers at the

ends thereof, pipes for connecting one of said headers to a water supply, and means associated with said heater and operable from without said compartment whereby the effect of combustion products from said burner on water in said water heater may be varied.

2. The combination with a compartment of a gas range of a heating unit comprising, a closed chamber having an opening in a wall thereof and a burner therein, a secondary closed chamber having a flue therein, a tubular connection between the upper parts of said chambers, a water heater removably disposed in the first-named chamber adjacent said opening therein, said water heater including spaced longitudinally-extending tubes and connecting headers at the ends thereof, pipes for connecting one of said headers to a water supply, means associated with said heater and operable from without said compartment whereby the effect of combustion products from said burner on water in said water heater may be varied, and a baffle in said secondary chamber for affecting the flow of combustion products traveling therein.

3. A heating unit insertable in and removable from a compartment of a gas range comprising in combination, a primary chamber having a burner therein, a secondary chamber having a flue therein, a tubular connection between the upper parts of said chambers, a water heater removably disposed in the primary chamber, said water heater including spaced longitudinally-extending tubes and connecting headers at the ends thereof, pipes for connecting one of said headers to a water supply and a pivoted gate associated with said water heater which is movable to direct the flow of combustion products from said burner through or around said water heater.

4. A heating unit insertable in and removable from a compartment of a gas range comprising in combination, a primary chamber having a burner therein, a secondary chamber having a flue therein, a tubular connection between the upper parts of said chambers, a water heater removably disposed in the primary chamber, a pivoted gate associated with said water heater which is movable to direct the flow of combustion products from said burner through or around said water heater, said water heater including spaced side walls and end headers with pipes between said headers and an upper wall spaced from said side and end walls, and pipes associated with one of said headers for connecting the same to a hot water supply.

5. A heating unit insertable in and removable from a compartment of a gas range comprising in combination, a primary compartment having a burner therein, a secondary compartment having a flue therein, a tubular connection between the upper parts of said compartments, a water heater connected to end headers removably disposed in the primary compartment and having walls at the sides of said pipes spaced to provide an open lower side, said water heater having pipes for connecting to a water supply and having a rotatable rod associated therewith, a gate secured to said rod and movable thereby to close said open lower side of the water heater when said rod is rotated, a lever pivoted to the outside of said primary compartment, and a link having one end pivoted to said lever and its other end connected to said rod.

6. A heating unit insertable in and removable from a compartment of a gas range comprising in

- combination, a primary compartment having a burner therein, a secondary compartment having a flue therein, a tubular connection between the upper parts of said compartments, a water heater 5 connected to end headers removably disposed in the primary compartment and having walls at the sides of said pipes spaced to provide an open lower side, said water heater having pipes for connecting to a water supply and having a rotatable rod associated therewith, a gate secured to said rod and movable thereby to close said open lower side of the water heater when said rod is rotated, a lever pivoted to the outside of said primary compartment, and a link having one end 10 pivoted to said lever and its other end connected to said rod, said primary compartment and water heater having co-operating means whereby said heater may be suspended within a compartment, of a gas range.
- 20 7. A heating unit insertable in and removable from a compartment of a gas range comprising in combination, a primary compartment having a burner in its lower side and an opening in a wall thereof above said burner, a secondary compartment having a flue therein, a tubular connection between the upper parts of said compartments, a water heater removably disposed in the primary compartment adjacent said opening, said heater having spaced side walls and end headers and an 25 upper wall spaced above said side and end walls to provide an open lower side with tubular members extending between said headers, spaced brackets carried by said heater adjacent said lower side having a rotatable rod journaled therein and a gate secured to said rod and movable thereby to close said lower side of the water heater compartment when said rod is rotated, said rod having an offset crank extending outwardly of said primary compartment whereby 30 said rod may be rotated from without the said compartment.
8. A heating unit insertable in and removable from a compartment of a gas range comprising in combination, a primary compartment having a burner therein and an opening in a wall thereof above said burner, a secondary compartment having a flue therein, a tubular connection between the upper parts of said compartments, inwardly extending ledges in opposite walls of the 35 primary compartment, a water heater removable supported in the primary compartment on said ledges, said water heater having spaced side walls and end headers to provide an open lower side for said heater with pipes extending between said headers, pipes extending from one header for connecting the water heater to a water supply, and means whereby said open lower side of the water heater may be closed from without the primary compartment.
- 40 9. The combination of a compartment struc-
- ture and water heater insertable in and removable therefrom, the said compartment structure having upper, lower, side and end wall members with certain wall members provided with a flue outlet and an opening for the insertion and withdrawal of said water heater, the said water heater including an upper wall, spaced side walls and end headers providing a structure open at its lower side with spaced water pipes extending between said end headers and across said opening, a gate pivoted to said water heater for swinging movements towards and away from the lower open side of said heater, operating mechanism for said gate associated with said compartment, and engageable connections associated with said mechanism and gate to facilitate connection of the gate and mechanism when the water heater is in said compartment.
10. The combination of a compartment structure and water heater insertable in and removable therefrom, the said compartment structure having upper, lower, side and end wall members with certain wall members provided with a flue outlet and an opening for the insertion and withdrawal of said water heater, the said water heater including an upper wall, spaced side walls and end headers providing a structure open at its lower side with spaced water pipes extending between said end headers and across said opening, a gate pivoted to said water heater for swinging movements towards and away from the lower open side of said heater, means for supporting the water heater in said compartment, operating mechanism for said gate associated with said compartment, and engageable connections associated with said mechanism and gate to facilitate connection of the gate and mechanism when the water heater is in said compartment.
- 15 11. The combination of a compartment structure and water heater insertable in and removable therefrom, the said compartment structure having upper, lower, side and end wall members with certain wall members provided with a flue outlet and an opening for the insertion and withdrawal of said water heater, the said water heater including angularly disposed longitudinally extending walls and end headers arranged to provide a compartment having an open side with water pipes extending between said end headers in said compartment across said opening, a gate pivoted to said water heater for swinging movements towards and away from the lower open side of said heater, operating mechanism for said gate associated with said compartment, and engageable connections associated with said mechanism and gate to facilitate connection of the gate and mechanism when the water heater is in said compartment.

HOMER D. DUFault. 60
